HOSE REEL

Vernon R. Kloefkorn, 4205 SE. 17th St.,
Edmond, Okla. 73034

Filed Jan. 11, 1971, Ser. No. 105,780

Term of patent 14 years

Int. Cl. D8—08

U.S. Cl. D8—222

FIG. 1 is a side elevational view of a hose reel constructed in accordance with the present invention,

FIG. 2 is an elevational view showing the other side of the hose reel shown in FIG. 1,

FIG. 3 is an end view of the hose reel shown in FIG. 1, and

FIG. 4 is a top view of the hose reel of FIG. 1.

I claim:

The ornamental design for a hose reel, substantially as shown.
